SHOW CASE CONSTRUCTION

Edward Walters, Toledo, Ohio, assignor to Toledo Mirror Paint & Glass Company, Toledo, Ohio, a corporation of Ohio

Application February 5, 1934, Serial No. 709,744

6 Claims. (Cl. 312—140)

This invention relates to show case structures, but particularly to show cases having glass panels, and an object is to produce a simple and efficient case which can be readily set up or taken down, which is sturdy and reliable in construction, and is provided with the novel features herein-after described, facilitating connecting of the panels together without the use of securing devices which extend through the panels themselves, thereby providing a reliable construction which militates against breakage and insures an exceptionally satisfactory assembly.

Other objects and advantages will hereinafter appear, and, for purposes of illustration, but not of limitation, an embodiment of the invention is shown on the accompanying drawing, in which:

Figure 1 is a side elevation of a show case;

Figure 2 is a transverse sectional elevation on the line 2—2 of Figure 1;

Figure 3 is a perspective view showing the channel devices for securing together adjoining panels;

Figure 4 is a perspective view of one end portion of a panel of the end portion of a channel;

Figure 5 is a sectional elevation on the line 5—5 of Figure 1;

Figure 6 is a sectional elevation showing the securing means for the lower end portion of the panels;

Figure 7 is a perspective view showing adjacent panels assembled with the top or covering plate in place;

Figure 8 is a perspective view of a portion of the rear end of the case showing the manner in which the sliding panels are mounted; and

Figure 9 is a perspective view of an end portion of one of the end panels.

The illustrated embodiment of the invention comprises a show case which is mounted on a suitable base 10, which may be of wood, or any suitable material, which supports the case and which is provided with end panels 11, a front panel 12, sliding rear panels 13 and 14, and a top or covering panel 15. Each of the panels is of glass, and is supported in a substantially U-shaped metallic channel 16 with which ears 17 are formed integrally, and project at substantially right angles to receive screws 18 for securing the ears to the support 10. Preferably, the ears 17 are formed by cutting out the metal from the channel member and bending the same to the desired position. Any suitable number of ears 17 may be employed as desired.

Embracing the upper edges of the side panel 12 is a sheet metal channel member 19 of substantially U-shaped construction. The panel mem-

ber 19 is of approximately the same length as the panel 12, and opposite end portions of the member 19 are bent inwardly to provide an inwardly extending lip 20, which projects beyond the opposite side of the panel 19. The lip 20 provides a finished appearance to the assembly and covers the upper edge portion of the panel 12. In the rear or inner flange of the channel member 19 is formed a slot 21, and the panel 12 in the region of the slot 21 is cut away, as indicated at 22, for a purpose hereinafter described. Provided within the top of the channel 19 is an opening 23 to receive a screw, as will hereinafter be explained. It will be understood that opposite ends of the channel 19 are similarly formed.

Embracing the upper edge portion of each of the end panels or plates 11 is a channel 24, and the panel at the end portions of the channel is cut away slightly, as indicated at 25. The metal at the end portions of the channel 24 is bent downwardly, as indicated at 26, over the cut-away portion 25, and then projects outwardly at substantially right angles to provide a tongue 27 which lies in a plane substantially parallel with the upper surface of the channel 24. The tongue 27 is adapted to enter the slot 21 in the channel 19, and, as shown in Figure 5, a screw 28 extends through the opening 23 in the channel 19 and screws into an opening 29 in a tongue 27, the opening 29 being screw-threaded to receive the screw 28. It will thus be seen that the parts can be readily and conveniently fastened together, and, contrary to the usual practice, it is not necessary to insert fastening devices through holes cut in the glass panels, these being decidedly unsatisfactory since they materially weaken the assembly.

Secured by screws 30 to the rear end of the channel 24 is a member 31 having an outwardly projecting tongue 32. The member 31 is also fastened to a channel member 33, which embraces the rear edge portion of the respective end panel 11. The tongue 32 is similar to the tongue 27 in that it is adapted to project through a slot 34 formed by a channel 35, which receives a sliding panel 13 providing a door for the case. The channel 35 has a rearwardly projecting flange 36, which overlaps a vertically disposed channel 37 for the panel 13, and connects to a channel 38 for the panel door 14. It is to be understood that the lower edges of the panels 13 and 14 rest in the lower supporting channel 16, and are free to slide horizontally in the usual manner. Opposed edges of the top or covering panel 15 are embraced by channel members 39, the ends

of which are provided with tongues 40, which are bent over the adjacent edge of the panel. Integral with each of the channel members 39 are ears 41, which are cut out similar to the ears 17 above described. The ears 41 extend vertically downward, and are secured by screws 42 to the adjacent channel members 24.

From the above description it will be apparent that I have provided a show case which can readily and conveniently be put together by an inexperienced person without the use of special tools or equipment. Not only is the assembly sturdy and reliable and one that will not be effected by warpage of the support, but, in addition, one which presents a pleasing, attractive and finished appearance. It will be further understood that the above described channel members for embracing the glass panels can be made from sheet metal stampings, very inexpensively so that the cost of the structure can be kept low.

It is to be understood that numerous changes in details of construction, arrangement and choice of materials may be made without departing from the spirit of the invention, especially as defined in the appended claims.

What I claim as new and desire to secure by Letters Patent is:

1. A show case construction having a pair of upwardly disposed panels arranged at substantially right angles to each other and means for securing said panels in place, said securing means comprising channel members embracing the upper edges of said panels, the end portion of one channel member extending downwardly over the end of the respective panel and then outwardly to provide a tongue, the adjacent channel member having a slot in one side to receive said tongue and the panel in the region of said slot being broken away to accommodate said tongue, and a fastener insertable from the outside engaging said adjacent channel member and tongue for securing said parts together.

2. A show case construction having a pair of upwardly disposed panels arranged at substantially right angles to each other and means for securing said panels in place, said securing means comprising channel members embracing the upper edges of said panels, the end portion of one channel member extending downwardly over the end of the respective panel and then outwardly to provide a tongue, the adjacent channel member having a slot in one side to receive said tongue and the panel in the region of said slot being broken away to accommodate said tongue, a fastener insertable from the outside engaging said adjacent channel member and tongue for securing said parts together, and a lip on said adjacent member covering the end thereof and extending in overlapping relation to the other channel member.

3. A show case construction having a pair of upwardly disposed panels arranged at substantially right angles to each other and means for securing said panels in place, said securing means comprising channel members embracing the upper edges of said panels, the end portion of one channel member extending downwardly over the

end of the respective panel and then outwardly to provide a tongue, the adjacent channel member having a slot in one side to receive said tongue and the panel in the region of said slot being broken away to accommodate said tongue, a fastener insertable from the outside engaging said adjacent channel member and tongue for securing said parts together, a lip on said adjacent member covering the end thereof and extending in overlapping relation to the other channel member, a panel for the top of the case, a channel member embracing opposite ends respectively of said top panel, an ear on said last channel member projecting downwardly therefrom, and means to secure said ear to a subjacent channel member.

4. A show case construction having a pair of upwardly disposed panels arranged at substantially right angles to each other and means for securing said panels in place, said securing means comprising channel members embracing the upper edges of said panels, the end portion of one channel member extending downwardly over the end of the respective panel and then outwardly to provide a tongue, the adjacent channel member having a slot in one side to receive said tongue and the panel in the region of said slot being broken away to accommodate said tongue, a fastener insertable from the outside engaging said adjacent channel member and tongue for securing said parts together, a lip on said adjacent member covering the end thereof and extending in overlapping relation to the other channel member, a channel member embracing the lower ends respectively of each panel, an ear integral with each of said last channel members, and means for securing said ears to a support.

5. A show case construction having a pair of upwardly disposed panels arranged at substantially right angles to each other and means for securing said panels in place, said securing means comprising channel members embracing the upper edges of said panels, the end portion of one channel member extending downwardly over the end of the respective panel and then outwardly to provide a tongue, the adjacent channel member having a slot in one side to receive said tongue, a fastener insertable from the outside engaging said adjacent channel member and tongue for securing said parts together, and a screw insertable from the outside through said adjacent channel member and in screw threaded engagement with said tongue.

6. A show case construction having a pair of upwardly disposed panels arranged at substantially right angles to each other and means for securing said panels in place, said securing means comprising members of sheet material engaging the upper edges of said panels, an outwardly extending tongue part on the end portion of one member, a part of the adjacent member being apertured to receive said tongue part, one of said parts having an offset bent to accommodate the other part, and a detachable fastener for securing said parts together.

EDWARD WALTERS.
